UNITED STATES PATENT OFFICE.

WALTER D. FORBES, OF OAKLAND, CALIFORNIA.

DESIGN FOR A SWIMMING-CAP.

56,123.

Specification for Design.

Patented Aug. 24, 1920.

Application filed June 24, 1918. Serial No. 241,713. Term of patent 14 years.

To all whom it may concern:

Be it known that I, WALTER D. FORBES, a citizen of the United States, residing at Oakland, county of Alameda, and State of California, have invented a new, original, and ornamental Design for Swimming-Caps, of which the following is a specification, reference being had to the accompanying drawing, forming part thereof.

The figure is a side elevation of a swimming cap, showing my new design.

I claim:

The ornamental design for a swimming cap, as shown.

WALTER D. FORBES.
